[57] ABSTRACT

A rotary solenoid comprises a ferromagnetic core assembly flux linked to an electromagnetic coil. The core assembly comprises confronting pole pieces having flat face portions spaced apart to define an air gap. The rotary solenoid includes a rotary assembly comprising a shaft adjacent said pole pieces journaled to said core assembly for rotation about an axis perpendicular to said pole faces. The rotary assembly includes an armature plate fixed to said shaft and projecting outwardly from said shaft for entry into said air gap. The rotary solenoid includes non-magnetic spacer members, one disposed on each side of said armature plate, said spacer members sized with said armature plate for a close fit between said pole faces, said spacer members cooperating with said pole faces to restrain said rotary assembly against axial movements.

ROTARY SOLENOID

BACKGROUND OF THE INVENTION

1. Field of the Invention

This invention relates to rotary solenoids and more particularly to rotary solenoids capable of executing large rotary strokes.

2. Description of the Prior Art

A rotary solenoid capable of executing a large rotary stroke is illustrated in U.S. Pat. No. 3,435,394. This patent teaches the use of an armature whose apparent center of mass coincides with the axis of armature rotation. The armature is thus gravitationally balanced about the axis of rotation. To achieve this gravitational balance, the armature is made substantially symmetric on diametrically opposite sides of its axis of rotation. The armature rotates in a solenoid energized core assembly which has two diametrically opposite pairs of pole pieces. To provide up to 180° armature rotation, diametrically opposite sides of the armature are oppositely canted and diametrically opposite ones of the pole pieces are also oppositely canted. The canting gives the armature a position of high magnetic reluctance spaced rotationally 180° from a position of low magnetic reluctance and, hence, a 180° stroke capability in response to energization of the solenoid coil. As the armature moves to its position of low reluctance, however, the prior art construction is such that the gravitationally balanced armature moves into a region of magnetic imbalance in which a high magnetically induced torque couple is developed which tends to twist the armature out of its plane of rotation. This couple subjects the bearings which rotationally mount the armature to a substantial radial loading which leads to a premature bearing failure.

SUMMARY OF THE PRESENT INVENTION

In the present invention, canted surfaces on the armature and pole pieces have been eliminated and instead an armature plate with flat parallel surfaces is permitted to move between confronting pole faces having flat parallel surfaces. This construction permits the armature to move into an air gap between the pole pieces without the development of a magnetically induced force couple such as would radially load the bearings which mount the shaft for rotation. To assure that the armature will move freely between the aforementioned pole faces, without seizing against either pole face, non-magnetic spacers which engage the opposite surfaces of the armature are sized to snugly fit into the air gap along with the armature so as to support the armature against axial motion while progressing through the air gap.

Stated briefly, the prior art has sacrificed magnetic balance to obtain gravitational balance. The present invention, recognizing that the magnetic forces attracting an armature far exceed the gravitational forces working on the armature, sacrifices gravitational balance in order to obtain magnetic balance.

A particular benefit derived from the present invention because the armature need not be gravitationally balanced, is that the armature may be a plate portion having the shape of a segment of an annulus extending between leading and trailing edges, said leading and trailing edges delimiting a notch diametrically opposite the aforesaid segment into which stop means may proj-

ect. Such a construction is not feasible when the armature is to be gravitationally balanced.

An object of the present invention is to provide a new and improved rotary solenoid device.

Another object of the present invention is to provide a rotary solenoid in which magnetic forces tending to deflect an armature from its allowed path of rotary movement are minimized.

A further object of the present invention is to provide a rotary solenoid utilizing an armature provided with an arcuate notch into which stop means to limit the rotation of the armature may project.

Other objects and advantages reside in the construction of parts, the combination thereof, the method of manufacture and the mode of operation, as will become more apparent from the following description.

BRIEF DESCRIPTION OF THE DRAWINGS

FIG. 1 is a perspective view with a portion broken away illustrating a rotary solenoid device embodying the present invention.

FIG. 2 is a section view taken substantially in the direction indicated by the line 2—2 of FIG. 1.

FIG. 3 is a section view taken substantially in the direction indicated by the line 3—3 of FIG. 2, but with the solenoid coil removed and the full circumference of the coil housing shown.

FIG. 4 is a section view taken substantially in the direction indicated by the line 4—4 of FIG. 2 with the solenoid coil removed and the full circumference of the coil housing shown.

FIG. 5 is a section view taken substantially in the direction indicated by the line 5—5 of FIG. 2 with the solenoid coil removed and the full circumference of the coil housing shown.

FIG. 6 is a fragmentary perspective view illustrating a modification.

DETAILED DESCRIPTION OF THE PREFERRED EMBODIMENT

The rotary solenoid illustrated in FIG. 1 comprises a unitary ferromagnetic housing 10 which encloses and is flux-linked to an electromagnet coil 18. The housing 10 comprises a tubular wall member 12 and end plates 14 and 16 which are press fitted into the opposite ends of the wall member 12.

Apertures such as shown at 19 bored radially through the wall member 12, there being two such apertures, receive conductors 20 and 22 which connect electrically to the opposite ends of the coil 18. Each of the conductors 20 and 22 is surrounded with insulation 24 and is further protected from electrical contact with the wall member 12 by an insulating sheath 26. The conductors 20 and 22 provide a means for connecting a source of power to the coil 18 so as to energize the coil 18. The power source, not shown, is preferably a direct current source.

The end plate 14 has an axial bore 28 at the center thereof. The end plate 16 has a similarly located bore 30. The bores 28 and 30 receive sleeve bearings 32 and 34, respectively, which journal a rotary assembly comprising a non-magnetic shaft 36. Fixedly mounted to the shaft 36 by means of knurling 37 is a ferromagnetic armature 38. The shape of the armature 38 appears in FIG. 4 where it can be noted that the armature 38 is a generally semi-cylindrical plate or annulus projecting laterally outwardly from the shaft 36. The armature has

flat sides and an arcuate outer margin 39 connecting between a trailing radial margin 40 and a leading radial margin 42. The open area of the armature between the leading and trailing margins is, in reality, a 180° notch which, as will be described, receives a stop pin 54 used to define the starting and stopping positions for the armature. It can be noted in FIG. 4 that the armature is not an exact semicircle because the central portion of the armature defines an annular hub 44 which siezes upon the knurling 37 on the shaft 36.

The side of the end plate 14 which confronts the coil 18 appears in plan view in FIG. 3. Projecting axially into the coil 18 from the end plate 14 is a pole piece 46 formed integrally on the end plate 14. It can be seen in FIG. 3 that this pole piece 46 is generally of semi-cylindrical shape but has its diametric margin 48 interrupted by a first semicircular recess 52 receiving the stop pin 54 and a second semicircular recess 50 which is a margin of the bore 28.

The end plate 16 is constructed similar to the end plate 14 and has a generally semi-cylindrical pole piece 60 integrally formed thereon. The end plate 16 can be seen in plan view in FIG. 5.

The surface configuration of the end plate 16 can be seen in FIG. 1 and the surface configuration of the end plate 14 is the same. The end plate 16 has an outer, axially thin, annular section 61 which is sized to receive the radial dimension of the coil 18. The end plate 16 also has a slightly thickened pad 63 which cooperates with the pole piece 60 to define the interior margin of the annular section 61 and thus support the coil 18 in concentric relation to the shaft 36. The pole pieces 46 and 60 have flat confronting generally semi-annular face portions which are perpendicular to the shaft 36, and which define an air gap between the pole pieces.

As best seen in FIG. 5, the pole piece 60 also has its diametric margin 65 interrupted by a first semicircular recess 67 receiving the aforementioned pin 54 and a second semicircular recess 69 which is a margin of the bore 30. The semicircular recess 52 described with reference to the end plate 14 and the semicircular recess 67 described with reference to the end plate 16 are produced by axial bores through the end plates 14 and 16 which are sized to receive the pin 54. The pin 54 is press fitted into the end plates 14 and 16 during the same operation by which the end plates 14 and 16 are press fitted into the wall member 12. Prior to this press fitting, however, annular spacers or bearings 62 and 64, which are non-magnetic, are positioned about the shaft 36 and in contact with the opposite sides of the armature plate 38. Also, prior to the time the aforescribed press fitting is accomplished suitable mounting studs 71, which may be threaded, are countersunk in suitably located apertures in the end plate 14, these mounting studs appearing in FIG. 1.

The extent of axial movement of the end plates 14 and 16, one toward the other, permitted during the press fitting thereof into the wall member 12 is controlled so that the air gap between the confronting pole pieces 46 and 60 will remain sufficient to receive the combined axial thicknesses of the armature plate 38 and the spacers 62 and 64 without frictionally restraining free rotation of the armature plate 38. This control may be achieved by assigning proper tolerances to the axial thicknesses of the pole pieces 46 and 60 and to the axial thickness of the wall member 12 and allowing the press mechanism which presses the end plates 14

and 16 into the wall member to bottom against the end surfaces of the wall member 12.

Affixed to the outer surface of the end plate 14, as by spot welding, not shown, is a cage member 74 which has an annular ring of upright posts 76 struck upwardly therefrom. The posts 76 form a cage for receiving a spiral spring 66. The inner end 68 of the spring 66 is fitted into a suitably shaped notch, not shown in detail, formed in the shaft 36. The outer convolution 70 of the spring 66 has a tongue 72 struck outwardly therefrom for hooking engagement with any one of the posts 76. The particular post 76a selected for hooking engagement by the tongue 72 is so selected that a desired bias will operate on the shaft 36 to press the leading margin 15 of the armature 38 against the pin 54. Having reference to FIG. 1, the bias operates to press the armature plate 38 in the counterclockwise direction against the pin 54.

As best shown in FIGS. 4, 5 and 6, the central axis of the pin 54, which serves as a stop pin positioned in a 180° armature notch, is aligned with the diametric edges 48 and 65 of the pole pieces 46 and 60. The diameter of the pin 54 is sufficient that when the trailing margin 40 of the armature plate 38 engages the pin 54 the leading margin 42 is displaced rotationally a small angle into the air gap between the pole pieces 46 and 60. By way of illustration, this angle may be 10° with the result that the leading margin 42 of the armature 38 is able to rotate 160° in the counterclockwise direction as appears in FIG. 4 to engage the diametrically opposite side of the pin 54.

It can be noted that the leading margin 42 of the armature 38 never leaves the air gap between the pole pieces 46 and 60. Likewise, it can be noted that the trailing margin 40 never enters the air gap between the pole pieces. Since the leading margin 42 remains always in the air gap, it is apparent that the leading margin 42 will encounter substantially the same magnetic flux, when the coil 18 is energized, regardless of the rotational position of the armature 38. Accordingly, with the armature 38 in its starting position, as illustrated in FIG. 4, an energization of the coil 18 will cause the armature 38 to progress in the clockwise direction, delivering always a substantially uniform torque to the shaft 36 until ultimately coming to rest when its leading margin 42 engages the stop pin 54. Such motion can be characterized as a movement from a starting position of high reluctance toward a position of lower reluctance to the magnetic flux produced by the coil 18.

One of the particular benefits to the construction described is that the preferably, but not necessarily, non-magnetic spacers 62 and 64 coact with the flat faces of the pole pieces 46 and 60 to support the armature 38 centrally in the air gap. This assures that the magnetic forces tending to pull the armature axially in the air gap are substantially opposite and balanced and accordingly, the armature 38 exerts no appreciable force couple tending to twist the shaft 36 and thereby load the bearings 32 and 34. There is a gravitational imbalance to the armature 38 because its mass is disposed to one side of the shaft 36, however, this gravitational imbalance is a minor component of force readily supported by the spacers 62 and 64 with only a nominal radial loading being applied to the bearings 32 and 34.

Those skilled in the art will realize that, absent the pin 54 or some alternative means to control the starting and stopping positions of the armature 38, a 180° armature plate exactly aligned with the substantially

180° pole pieces 46 and 60 will experience no torque upon energization of the coil 18. Thus, if the armature 38 were permitted to occupy a position with its semi-annular plate portion entirely outside the air gap, or alternatively, entirely inside the air gap, the armature would be in a labile position. Even in the embodiment shown, the armature 38 is so closely approaching a labile position at the end of its power stroke produced by energization of the coil 18 that it may be unable to overcome the opposing bias of the spring 66. For this reason, the opposing bias of the spring 66 is normally made as small as can be accepted for the operating function to be performed by the rotary solenoid. Of course, when the load attached to the shaft 36 imposes a substantial resistance to return of the shaft after the rotary solenoid has accomplished its power stroke, the return spring 66 must be proportionately strong and one can encounter operating requirements which tax the ability of the armature to execute a full power stroke.

The modification shown in FIG. 6 discloses one expedient that can be employed in cases when the armature spring requirements overtax the capability of the armature to execute its full power stroke.

In the modification of FIG. 6, the primary changes reside in the end plate construction and more particularly the pole piece construction. Elements of the modification which are the same as a corresponding element described with respect to the preferred embodiment bear the same reference numbers as employed in describing the preferred embodiment. Elements of the modification which are different than corresponding elements described in reference to the preferred embodiment are distinguished in FIG. 6 by the suffix *a*. A comparison of FIGS. 1 and 6 will reveal that the modified pole pieces 46a and 60a are rotated 180° with respect to the corresponding pole pieces illustrated in FIG. 1. This change in the manner of illustrating the modification was employed so as to better illustrate the differences between the preferred embodiment and the modification:

As apparent in FIG. 6 the pole pieces 46a and 60a have been modified by adding a wing 80 to the pole piece 46a and the wing 82 to the pole piece 60a. The wings 80 and 82 project axially one toward the other, without touching one another, and occupy a small portion of what was air gap in the preferred embodiment. It can be noted that the wings 80 and 82 are generally pie shaped when viewed in directions parallel to the axis of the shaft 36. It can also be noted that the pole pieces 46a and 60a have flat confronting, generally semi-annular face portions except where interrupted by the wings 80 and 82.

In the modification of FIG. 6 the stop pin 54 is located adjacent pole pieces 46a and 60a and essentially in contact with such pole pieces. Thus, the stop pin 54 of the modification is not received partially within one of the radial margins of each pole piece as was the case in the preferred embodiment. The only other difference between the preferred embodiment and the modification resides in the direction in which the armature 38 is biased. Thus, the armature 38 of the modification is biased in the clockwise direction as appears in FIG. 6 and accordingly, FIG. 6 illustrates the armature 38 after the modification of FIG. 6 has been energized and has taken its power stroke.

An obvious advantage offered by the embodiment of FIG. 6 is that, as the armature 38 approaches the end of its power stroke during the time the electromagnet coil is energized, the leading margin of the armature approaching the wings 80 and 82 is magnetically attracted to these wings. The wings thus enable the armature to deliver a higher torque to the shaft 36 as the armature approaches the end of its power stroke. As a result, the armature 38 is better equipped to overcome the bias of the return spring and is able to complete its power stroke with greater certainty than is the case for the preferred embodiment.

It will occur to those skilled in the art that the same benefits as described with reference to the modification of FIG. 6 may be obtained by erecting the wings 80 and 82 on the trailing edge of the armature plate 38. In some applications, this alternate construction, which is not shown in the drawings, will offer the further advantage that the armature need not physically contact any part of the pole pieces and thus there will be no need to overcome a magnetic retention between the armature and the pole pieces.

Although the preferred embodiment of the device has been described, it will be understood that within the purview of this invention various changes may be made in the form, details, proportion and arrangement of parts, the combination thereof and mode of operation, which generally stated consist in a device capable of carrying out the objects set forth, as disclosed and defined in the appended claims.

Having thus described my invention, I claim:

1. In a rotary solenoid, the combination comprising a coil, a ferromagnetic core assembly flux linked with said coil, said core assembly including a pair of confronting plate members each having a pole piece projecting therefrom, said core assembly including means supporting said plate members in spaced apart relation, said pole pieces projecting one toward the other and having flat parallel face portions spaced apart to define an air gap therebetween, a rotary assembly including a shaft and an armature fixed to said shaft, means mounting said shaft to said core assembly for rotation about an axis perpendicular to said face portions, said armature comprising a ferromagnetic plate portion having flat sides perpendicular to said axis, said plate portion projecting outwardly from said shaft for movement in said air gap, non-magnetic spacer members encircling said shaft and contacting opposite sides of said plate portion, said plate portion and said spacer members received between said face portions, said spacer members contacting said face portions to support said plate portion against axial movement relative to said pole pieces.

2. The rotary solenoid of claim 1 wherein said plate portion has an arcuate margin connecting from a radially disposed leading margin to a radially disposed trailing margin, said arcuate margin subtending an angle not exceeding 180° between said leading and trailing margins.

3. The rotary solenoid of claim 2 in which said arcuate margin subtends an angle of 180° between said leading and trailing margins.

4. The rotary solenoid of claim 3 wherein each said face portion is an approximate 180° annular segment concentric to said rotary axis, and including stop means coacting between said core assembly and said rotary assembly to confine said rotary assembly to rotary posi-

tions in which a part of said plate portion remains in said air gap.

5. The rotary solenoid of claim 4 wherein said stop means comprises a pin member extending between said end plates, a portion of said pin member projecting into said air gap for engagement with the leading margin of said plate portion.

6. The rotary solenoid of claim 5 including resilient means coacting between said rotary assembly and said core assembly to bias said rotary assembly to a position in which the trailing margin of said plate portion engages said stop means, said plate portion, upon energization of said coil, being urged magnetically through said air gap against the bias of said resilient means.

7. The rotary solenoid of claim 6 wherein said pole pieces have wing means to augment the magnetic urging of said plate portion.

8. In a rotary solenoid of the type comprising a coil, a ferromagnetic core assembly flux linked with said coil, said core assembly including a pair of pole pieces having flat parallel face portions spaced apart to define an air gap therebetween, and a rotary assembly including an armature supported for rotation about an axis perpendicular to said face portions, said armature including a ferromagnetic plate portion having flat sides

25

perpendicular to said axis and movable in said air gap, the improvement comprising non-magnetic bearing means disposed in said air gap and coacting with said pole pieces to support said plate portion centrally in said air gap and away from contact with said face portions.

9. In a rotary solenoid of the type comprising a coil, a ferromagnetic core assembly flux linked with said coil, said core assembly including a pair of pole pieces having flat parallel face portions spaced apart to define an air gap therebetween, and a rotary assembly including an armature supported for rotation about an axis perpendicular to said face portions, said armature including a ferromagnetic plate portion having flat sides

10

perpendicular to said axis and movable in said air gap, the improvements wherein said plate portion is an annular segment concentric to said axis of rotation, said plate portion having a radially disposed leading margin for movement through said air gap and having a radially disposed trailing margin, and wherein said armature or one of said pole pieces includes wing means projecting axially therefrom to augment magnetic attraction between at least one of said pole pieces and said armature.
